UNITED STATES PATENT OFFICE.

ANDREW J. HOENES, OF MURRAY, UTAH.

MEDICAL ELECTRIC-CURRENT REGULATOR.

1,078,787.

Specification of Letters Patent.

Patented Nov. 18, 1913.

Application filed October 21, 1912. Serial No. 727,041.

To all whom it may concern:

Be it known that I, ANDREW J. HOENES, a citizen of the United States, residing at Murray, in the county of Salt Lake and State of Utah, have invented a new and useful Medical Electric-Current Regulator in which a rheostat is introduced into the circuit in such a manner that the current may be efficiently regulated thereby.

10 The objects of my invention are, first to provide a rheostat in a glass cylinder, so that it may be protected from accidental touch and yet be visible and easily accessible; secondly to provide a rheostat of such construction that the ordinary electric lighting current may be adapted to medical use.

15 A further object of the invention is to provide a novel and improved resistance element.

20 I attain these and other objects by the device illustrated in the accompanying drawing, in which single figure is a perspective view of the whole device.

Referring now to the drawing, 1 is the incoming wire from the source of electrical energy, and 2 is the outgoing wire. These wires are connected by the ordinary plug with any lamp socket. These wires pass along through grooves in the under side of 25 the insulating base 3 to the electric light bulbs 4, 4, thence one wire passes to the post 5, the other to the post 6. A rod having an insulated handle 8, passes through the slot 9 in the post 5 and has on its opposite and 30 inner end a sponge 10 forming one electrode. The other electrode 11 is firmly attached to the insulated end 12' of a rod 12, which latter passes through a hole in the post 14 and is provided with an insulated handle 13.

35 A wire connects post 14' with post 15, and a conductive spring 24 connects electrode 11 with post 14'. Into the holes in posts 6 and 15 are passed the contact points of the cords 16 and 17, attached to the electrode plates 18 and 19. It will be observed that if a patient places one foot on the plate 18 and the other on 19 that the circuit is closed with the exception of the break between electrodes 10 and 11.

40 By moistening the sponge electrode 10 the current may be increased, the amount of current transmitted depending on the dampness of the sponge.

45 In operation, the operator grasps the handle 13 and pushes the rod attached thereto inward toward the sponge 10 until the cur-

rent passes from one electrode to the other and through the patient in contact at 18 and 19. The amount of current transmitted depends upon the approximation of the electrodes to each other and upon the compression of the damp sponge by the pressure of the electrode 11 upon it.

It will be seen that the introduction of the sponge electrode in the circuit and that by bringing the poles of the regulator nearer together the amount of the current transmitted will be increased.

To insulate the poles of the regulator and their electrodes I inclose them in the glass cylinder 20 which is held to the insulating base 3 by strips 21, 21. By loosening the screw 22 the sponge with its rod may be removed for moistening by a side motion through the slot 9. By tightening the screw 22 the rod 7 may be held in position so that the position of the sponge is fixed, or the operator may by intermittent adjustment of the poles of the regulator produce an undulating current, the spring 24 retracting the electrode 11.

It will be observed that no greater amount of current can be transmitted to the patient than the conductivity of the electrode 10 will transmit, and also that the lights 4, 4, indicate when the current is on or off, and that no greater current can pass to the patient than the filament of the lights can carry without burning out.

I find that by use of this apparatus a physician can utilize the ordinary electric lighting system for medical purposes thus doing away with medical batteries.

It will be understood that the lamps may be dispensed with in case batteries or other source of electric current are used, and the current passed direct to the regulator.

Having thus described the construction and operation of my invention what I claim as new and desire to secure by Letters Patent is—

1. A resistance element comprising a sponge moistened with a conducting fluid.
2. A resistance element comprising a sponge moistened with water.
3. An electric current regulator comprising a non-conductive tube, a rod extending into the tube and removable therefrom, a compressible resistance element in the tube, said element being carried by the rod and removable therewith from the tube, a support for the rod on the outside of the tube,

said support having a recess in which the rod removably seats, and means for locking the rod in said recess.

4. An electric current regulator comprising a non-conductive tube, electrodes in the tube, one of which electrodes is movable toward and from the other, an operating rod connected to the movable electrode, and resilient means for normally holding the movable electrode retracted.

5. An electric current regulator comprising a non-conductive tube, electrodes in the

tube, one of which electrodes is movable toward and from the other, an operating rod connected to the movable electrode, and a 15 spring electrically connected to the movable electrode and normally holding said electrode retracted.

In witness whereof I have hereunto set my hand this 10th day of October 1912.

ANDREW J. HOENES.
